CLAIM

The ornamental design for a display mounting apparatus, as shown and described.

DESCRIPTION

FIG. 1 is a front view of a display mounting apparatus showing our new design.

FIG. 2 is a rear view thereof.

FIG. 3 is a left side view thereof.

FIG. 4 is a right side view thereof.

FIG. 5 is a top side view thereof.

FIG. 6 is a bottom side view thereof.

FIG. 7 is a front perspective view thereof; and,

FIG. 8 is a rear perspective view thereof.

The broken lines depict portions of the display mounting apparatus that form no part of the claimed design.
